UNITED STATES PATENT OFFICE.

FRED ASHWORTH, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

THREAD-WAXING DEVICE.

1,298,638.

Specification of Letters Patent.

Patented Apr. 1, 1919.

Application filed July 11, 1917. Serial No. 179,976.

To all whom it may concern:

Be it known that I, FRED ASHWORTH, a citizen of the United States, residing at Beverly, in the county of Essex and State 5 of Massachusetts, have invented certain new and useful Improvements in Thread-Waxing Devices; and I do hereby declare the following to be a full, clear, and exact description of the invention, such as will enable others skilled in the art to which it 10 appertains to make and use the same.

This invention relates to thread waxing devices, and more particularly to wax pots for waxing a plurality of threads for use 15 in a shoe sewing machine.

In sewing machines for sewing outsoles to the bottoms of shoes it is often desirable to use a different kind of thread for the shuttle than is used for the needle. These 20 threads may be of different colors and may be waxed with waxes of different colors or waxes of different chemical and physical properties.

The primary object of the present invention 25 is to provide a thread waxing device for an outsole sewing machine by which the shuttle and needle threads may be waxed separately with different kinds of waxes and by which different kinds of waxes having 30 different specific heats may be held in proper condition to impregnate the thread.

In accordance with this object a feature 35 of the invention contemplates the provision in a thread waxing device of a heating member and a plurality of separate wax receptacles independently mounted for movement relatively to said heating member.

Other features of the invention consist in 40 certain features of construction and combinations of parts, the advantages of which will be apparent to those skilled in the art from the following description.

The various features of the invention are 45 illustrated in the accompanying drawings in which Figure 1 is a top plan view of a wax pot embodying the invention in its preferred form; Fig. 2 is a view in side elevation of the wax pot; and Fig. 3 is a view in rear elevation of the wax pot.

50 The thread waxing device illustrated in the drawings comprises a pair of separate wax pots 10 and 12 which are mounted on a supporting bracket 14 at opposite sides of a heating member 16. The wax pots 10

and 12 consist of hollow receptacles which 55 have the usual receiving compartment 18 for the unmelted wax and a thread waxing compartment 20 for the melted wax, which is separated from the compartment 18 by a perforated partition 22. Apertured lugs 60 24, formed on the front and rear faces of the wax pots, are slidably mounted on rods 26 which are secured in opposite ends of the support 14.

The heating member 16 consists of a flat, 65 hollow casting which is secured in fixed position to the lower face of the bracket 14. The member 16 is arranged to be heated by steam and has a steam inlet 28 and steam outlet 30. The wax pots are both heated 70 from the member 16 and may be shifted on the rods 26 to bring their rear faces directly into contact with the heating member.

The different kinds of waxes for waxing 75 the shuttle and needle threads may have different specific heats and require different amounts of heat to hold them in the proper molten condition to properly impregnate the thread. The temperature of the heating member cannot be varied to any great 80 extent when heating with pressure or exhaust steam, and in order to vary the amount of heat imparted to the wax, the wax pots are arranged to be adjusted toward and from the heating member. To adjust the 85

wax pots, adjusting bolts 32 are rotatably mounted in the outer walls of the wax pots and the inner ends of the bolts are threaded into lugs 34 formed on the lower face of the bracket 14. The adjustment of the wax 90 pots with relation to the heating member permits an accurate control of the amount of heat imparted to the wax and permits practically any kind of wax to be held in a molten state. When it is desired to first 95 melt the wax, the pot may be placed in direct contact with the heating member and after the wax is melted, the pot may be withdrawn from the heating member a sufficient distance to hold the wax in a molten 100 condition and still avoid boiling. Further, if it is not desired to continuously use the shuttle wax, the pot containing the shuttle wax may be withdrawn from the heating member a sufficient distance to hold the wax 105 in a semi-molten condition until it is desired to use it.

The thread to be waxed in the pot 10 en-

ters the wax pot through a guide 36 in the bracket 14, passes down through a porcelain eyelet 38 which is held by an arm 40 secured to the upper edge of the wax pot 10, and passes out through a wax stripper 42. From the wax stripper the thread passes over thread trucks 44 and 46 from which it may pass to the thread tension of the sewing machine. The thread to be 10 waxed in the pot 12 enters through a thread guide 48 in the bracket 14, passes down through an eyelet 50 supported on an arm 52 secured to the wall of the wax pot 12, and up through a wax stripper 54. From 15 the wax stripper the thread passes over a thread truck 56 and may be conducted directly to a bobbin winder. The thread guides 36 and 48 and strippers 42 and 54 are all held in a heated condition by the 20 heating member 16. The thread trucks 44, 46 and 56 are mounted on a bracket 58 which is supported on the inlet coupling 28, so that the thread trucks will be heated to hold the thread in heated condition as it leaves 25 the wax pot.

The preferred form of the invention having been thus described, what is claimed as new is:

1. A thread waxing device having, in combination, a heating member, a supporting member, and a plurality of separate wax receptacles independently mounted on said supporting member for movement relatively to said heating member. 30

2. A thread waxing device having, in combination, a heating member, a supporting member, a pair of separate wax receptacles, and means for supporting said receptacles on said supporting member at different distances from the heating member. 40

3. A thread waxing device having, in combination, a heating member, a supporting member, a plurality of wax receptacles movable with relation to said heating member, mounted on said supporting member, and a set of thread guiding devices for each wax receptacle mounted on the heating member. 45

FRED ASHWORTH.
